UNITED STATES PATENT OFFICE.

WILLIAM C. PEET, OF NEW YORK, N. Y., ASSIGNOR TO THE J. L. MOTT
IRON WORKS, OF SAME PLACE.

DESIGN FOR A STALL-GUARD.

SPECIFICATION forming part of Design No. 16,575, dated March 16, 1886.

Application filed February 10, 1886. Serial No. 191,521. Term of patent 14 years.

To all whom it may concern:

Be it known that I, WILLIAM C. PEET, of the city and State of New York, have invented a Design for a Stall-Guard, of which the following is a specification.

This design is shown in the accompanying printed picture; and it relates to the ornamental configuration of the guard that separates one stall from another. The narrow portion of this guard is open-work, and there is a circular ornament at the commencement of the rising portion of the guard and open-work in such guard, as well as the surface ornaments. The catharine-wheel open-work at A is adjacent to the open-railing work B, and there is a fluted ornamental post, C, at the end. The top rail of the guard is a com-

pound curve at D, and terminates as a scroll at E. There is an open lattice, F, diagonal ornamented band at G, circular leaflet ornament H, border I, and corner ornaments K L M, all in low relief, as represented.

I claim—

The design of the ornamental stall-guard having the railing and circular open-work and raised circular ornaments, borders, diagonal band, and corner ornaments, substantially as described and represented.

Signed by me this 2d day of February, A. D. 1886.

W. C. PEET.
